UNITED STATES PATENT OFFICE.

STEWART HARTSHORN, OF SHORT HILLS, NEW JERSEY, ASSIGNOR TO STEWART HARTSHORN COMPANY, OF EAST NEWARK, NEW JERSEY, A CORPORATION OF NEW JERSEY.

SHADE FASTENING.

Application filed November 13, 1920, Serial No. 423,936. Renewed August 28, 1924.

To all whom it may concern:

Be it known that I, STEWART HARTSHORN, a citizen of the United States, and a resident of Short Hills, county of Essex, and State of New Jersey, have invented a certain new and useful Shade Fastening, of which the following is a specification.

The invention relates to window shade rollers, and more particularly to devices for 10 securing the shade to the roller. The invention is illustrated and described in connection with a shade roller of the spring action type, but it is to be understood that it may be carried out with rollers of other types, 15 or for securing other articles, such as drapery, to poles or other supports.

The objects of the invention are to provide means for securing shades or the like to hollow members, such as tubular shade 20 rollers without interference with the contents of the roller; by means of which the shade may be firmly secured in place without injury to the roller; by means of which the shade may be secured to the roller continuously for the entire length of the 25 roller, whether the latter be of wood or metal; to provide means for securing the shade in position on the roller without the use of tools, and which will prevent puckering or wrinkling of the shade, and to provide 30 means whereby properly alining the shade on the roller may be facilitated.

These and further objects will more fully appear in the following specification and 35 accompanying drawings considered together or separately.

One embodiment of the invention is illustrated in the accompanying drawings in which like parts in all of the figures are 40 designated by corresponding characters of reference, and in which—

Fig. 1 is a plan view of a tubular shade roller provided with the invention, the shade being omitted.

Fig. 2 is an enlarged plan view of the fastening device.

Fig. 3 is a section on the line 3—3 of Fig. 2.

Fig. 4 is an end elevation of the fastener.

Fig. 5 is an end elevation taken from the opposite end.

Fig. 6 is a detail section, on a greatly enlarged scale, taken on the line 6—6 of Fig. 1, the shade being shown in position.

Figs. 7 and 8 are detail views of a modified form of fastener.

The invention will first be described in connection with a tubular sheet metal roller such as is commonly known as a "tin" roller. In the drawings 1 designates such a roller 60 which is rolled to form and soldered, as is common. One end of the roller is provided with a rectangular spear 2, and the opposite end carries a cylindrical pin 3 by means of which the roller with the shade 4 attached 65 is mounted in a window frame.

The roller is provided with a series of perforations 5 and an equal number of longitudinal slots 6, as shown, by means of which a fastening strip 7 may be secured 70 to the surface of the roller.

The strip is preferably curved laterally to conform to the surface of the roller, and is provided at one end with a spur 8 which projects longitudinally of the strip but on 75 a slightly lower plane. At the opposite end the strip is provided with a triangular lip 9 which is folded along its base and under the strip and parallel thereto for a portion at least of its length. The extremity of the 80 lip may be bent downward eccentrically with relation to the strip as shown in Figs. 5 and 6.

When it is desired to apply a shade to the roller, the end edge of the cloth is laid 85 longitudinally of the roller and in such a position that the perforations 5 and slots 6 are covered. The cloth over the perforation is now pierced by the spur 8 and the latter, when the strip is moved toward the 90 position parallel to the roller, is shoved forward into the bore of the roller, the slight bend 10 in the spur will permit the spur to lie parallel with, and against the wall of the roller when the body of the strip 95 is in position resting on the cloth and parallel with the outside of the roller.

Before the strip assumes the last mentioned position the apex of the lip 9 is pushed through the cloth and through the 100 slot 6 nearest the perforation 5. The lipped end is then moved laterally with respect to the roller, forcing the lip into the same and into frictional engagement with the wall of the bore thereof. The shade is then 105 folded back over the strip and around the roller in the direction opposite to that at which it was first laid. Additional strips

are similarly disposed along the roller whereby the entire edge of the cloth, except the slight gaps between the strips and short spaces at the ends of the roller, is securely attached to the roller while the cloth is perforated at relatively wide intervals only. The pull of the shade on being unwound will tend to hold the lip 9 in the slot 6, and the said slot may be of any length desired whereby strips of various lengths may be used.

Instead of placing the spur at the extremity of the strip as shown in Figs. 1, 2 and 3, the spur 22 may be cut out at some distance from the end of the strip 23 as shown in Fig. 7.

In Fig. 8 the lip 24, instead of being located at the end of the strip, as before, is positioned a short distance from the end. By the use of the construction illustrated in Figs. 7 and 8 the strips used at the ends of the roller may extend over the ferrules, when used, and to the extremities of the roller, and the shade will be secured to the roller for the entire length thereof.

In accordance with the provisions of the patent statutes the principle of the invention, together with what is now considered to be the best embodiment thereof, have been described, but it is to be understood that the apparatus described is merely illustrative, and that the invention may be carried out in other ways.

The invention having been described what is claimed and desired to be secured by Letters Patent, is:—

1. An article of the class described, comprising a roller, there being a perforation in the roller, a member adapted to extend longitudinally of the roller, means for engaging one end of the member within the perforation, there being a longitudinal slot in the roller, and means extending transversely of the roller for engaging the slot and securing the opposite end of the member to the roller.

2. A device of the character described, comprising a tubular sheet metal roller of uniform cross section, there being a perforation in the cylindrical surface of the roller, a member adapted to extend longitudinally of the outer surface of the roller and in proximity thereto, a spur projecting from the member and adapted to engage the interior wall of the roller, there being a longitudinal slot in the cylindrical surface of the roller and at a distance from the perforation, and means carried by the member and extending through the slot for elastically engaging the interior wall of the roller for securing the member to the roller.

3. A device of the character described, comprising a tubular sheet metal roller of uniform cross section, there being a perforation in the cylindrical surface of the roller,

a member adapted to extend longitudinally of the outer surface of the roller and in proximity thereto, an integral spur projecting from the member, said spur being on a different plane from the member and adapted to engage the interior wall of the roller, there being a longitudinal slot in the cylindrical surface of the roller and at a distance from the perforation, and offset means integral with the member for passing through the slot and elastically engaging the interior wall of the roller for securing the member to the roller.

4. A device of the character described, comprising a tubular roller, there being a series of spaced perforations in the roller, said series extending longitudinally of the roller, there being a series of longitudinal slots in the roller, each slot being in approximate alinement with a perforation, an elongated member extending longitudinally of the roller between a perforation and a slot, a spur carried by the member, said spur being on a plane different from the body of the member, whereby said spur may engage the interior wall of the roller through the perforation, a lip carried by the member, said lip extending below and substantially parallel and transversely of the member and adapted to engage the interior wall of the roller through the slot.

5. A device of the character described comprising a tubular roller, there being a series of spaced perforations in the roller, said series extending longitudinally of the roller, there being a series of longitudinal slots in the roller, each slot being in approximate alinement with a perforation, an elongated member extending longitudinally of the roller between a perforation and a slot, a spur carried by one end of the member, said spur being on a plane different from the body of the member, whereby said spur may be passed through a perforation and engage the interior wall of the roller by movement of the member longitudinally of the roller, a lip carried by the opposite end of the member, said lip extending below and substantially parallel to and transversely of the member and adapted to engage the interior wall of the roller through the slot by movement of the lipped end of the member transversely of the roller.

6. A device of the character described, comprising a tubular roller, there being a series of spaced perforations in the roller, said series extending longitudinally of the roller, there being a series of longitudinal slots in the roller, each slot being in approximate alinement with a perforation, an elongated member extending longitudinally of the roller and on the outside thereof between a perforation and a slot, a pointed spur carried by one end of the member, said spur being in a plane dif-

ferent from that of the body of the member, whereby said spur may be passed through a perforation and engage the interior wall of the roller through the perforation, by movement of the member longitudinally of the roller, a pointed lip carried by the opposite end of the member, said lip extending below and substantially parallel to and transversely of the member and adapted to engage the interior wall of the roller through the slot, by movement of the

lipped end of the member transversely of the roller, said lip being of the same curvature as the interior of the roller wall and engaging the same for a considerable distance circumferentially of the roller. ¹⁵

This specification signed and witnessed this ninth day of November, 1920.
